CLAIM

We claim the ornamental design for a mixer, as shown and described.

DESCRIPTION

FIG. 1 is a front isometric view of a mixer showing our new design.

FIG. 2 is a front elevation view thereof.

FIG. 3 is a back elevation view thereof.

FIG. 4 is a left side elevation view thereof.

FIG. 5 is a right side elevation view thereof.

FIG. 6 is a top plan view thereof; and,

FIG. 7 is a bottom plan view thereof.

The broken lines in the figure drawings represent unclaimed environment only and form no part of the claimed design.

1 Claim, 7 Drawing Sheets

Related U.S. Application Data

continuation of application No. 29/469,252, filed on Oct. 8, 2013, now Pat. No. Des. 715,267.
